SYRINGE

Filed Jan. 30, 1925

Inventor:
John W. B. Ladd,
J. W. B. Ladd,
Attest.

Patented June 16, 1925.

UNITED STATES PATENT OFFICE.

JOHN W. B. LADD, OF BOSTON, MASSACHUSETTS, ASSIGNOR TO RANDALL-FAICHNEY CORPORATION, OF BOSTON, MASSACHUSETTS, A CORPORATION OF MASSACHUSETTS.

SYRINGE.

Application filed January 30, 1925. Serial No. 5,736.

To all whom it may concern:

Be it known that I, JOHN W. B. LADD, of Jamaica Plain District, Boston, in the county of Suffolk and State of Massachusetts, a citizen of the United States, have invented an Improvement in Syringes, of which the following description, in connection with the accompanying drawings, is a specification, like characters on the drawings representing like parts.

This invention relates to a syringe of the class in which a flexible bulb is used to expel the liquid from the barrel, and is more particularly concerned with novel features relating to the protection of the rubber bulb, and the facility of cleansing the same.

The invention will be best understood by reference to the following description, when taken in connection with the accompanying drawing of one specific embodiment thereof, while its scope will be more particularly pointed out in the appended claims.

The single figure of the drawing is a central, longitudinal section of a syringe exemplifying the invention.

Referring to the drawing, and to the embodiment of the invention which is selected for exemplification, there is shown a syringe having a barrel 1, which in practice is usually made of glass, the same having a nozzle 2 appropriately shaped for the class of work which the syringe is intended to do, said nozzle having an orifice 3 for the discharge of the liquid under the influence of a flexible bulb 4, usually made of rubber. This bulb has a wall 5, which is snugly received in the adjacent end of the barrel 1, and is comparatively thin, thus presenting a relatively large opening 6, facilitating a thorough cleansing of the interior of the bulb.

A bushing 7, also received in the barrel, presents a capillary passage 8, which affords a way of communication between the chamber within the bulb and the chamber within the barrel, and permits air to be expelled from the bulb into the barrel, but prevents the entrance of liquid from the barrel into the bulb. In the present example, this bushing has a portion 9, which is received within and encircled by the wall 5, the latter therefore being interposed between that portion of the bushing and the surrounding wall of the barrel. The thickness of the wall 5 is somewhat greater than the two walls between which it is received, and therefore the

rubber is under compression and prevents leakage. In the present instance, the bushing presents a lateral enlargement, such as a circumferential bead or flange 10, which holds the rubber under even greater pressure at this point, and prevents leakage, while, at the same time, preventing the bulb from being accidentally withdrawn from its place.

The bushing may be, and herein is, provided with an enlarged portion or collar 11, which is separated from the internal surface of the barrel by a capillary space 12, which prevents the entrance of liquid at this point, thus protecting the adjacent end of the rubber ball 5 from the action of the liquid in the barrel, and also preventing contamination of the contents of the syringe by matter which might otherwise lodge at this point. This wall may also serve as an abutment for the end of the wall 5.

In the present instance, the bushing is made of glass, which is conveniently formed of a piece of tubing heated and appropriately shaped, and the capillary passage 8 is formed in a reduced portion or neck 13, which may have a tapered formation.

Herein, the rear end of the barrel, which receives the bulb, is provided with a laterally extending flange 14, which may be flared somewhat in order to facilitate the introduction of the bulb, and to form a funnel through which liquid may be poured into the barrel. The parts can be very readily cleansed by simply withdrawing the bulb from its place, carrying with it the bushing, after which the latter can be removed from the bulb, and all three parts then cleansed in a most thorough manner. The advantages of this construction will therefore be apparent.

Having thus described one embodiment of the invention, but without limiting myself thereto, what I claim and desire by Letters Patent to secure is:

1. In a syringe, the combination of a barrel, a bushing received in said barrel, and presenting a capillary passage, and a flexible bulb having a chamber communicating by way of said passage with said barrel, said bulb having a wall interposed between a portion of said bushing and the surrounding wall of said barrel.
2. In a syringe, the combination of a barrel, a bushing received in said barrel and

presenting a capillary passage, said bushing presenting a reduced portion, and a flexible bulb having a chamber communicating by way of said passage with said barrel, said bulb having a wall interposed between said reduced portion and the surrounding wall of said barrel.

3. In a syringe, the combination of a barrel, a bushing received in said barrel and presenting a capillary passage, said bushing having a portion which is separated from the surrounding wall of said barrel by a capillary space, said bushing having a reduced portion which is spaced from said wall, and a flexible bulb having a chamber communicating by way of said passage with

said barrel, said bulb having a wall interposed between said reduced portion and said surrounding wall of said barrel.

4. In a syringe, the combination of a 20 barrel, a part received in said barrel and presenting a capillary passage, a part presenting a shoulder within said barrel, and a flexible bulb having a chamber communicating by way of said passage with said barrel, 25 said bulb having a wall interposed between the first-mentioned part and the surrounding wall of said barrel and presented endwise against said shoulder.

In testimony whereof, I have signed my 30 name to this specification.

JOHN W. B. LADD.
